UNITED STATES PATENT OFFICE

2,381,441

STOCK STOP FOR METALWORKING MACHINES

Alfred E. Drissner and William J. Hogg, Cleveland, Ohio, assignors to The National Acme Company, Cleveland, Ohio, a corporation of Ohio

Application October 7, 1943, Serial No. 505,294

12 Claims. (Cl. 10—107)

This invention relates to an improvement in stock stops for metal working machines such as pipe coupling tapping machines and has for its principal object the provision of a stock stop or work positioning means which will be simple in construction, efficient in use and comparatively inexpensive to manufacture.

A further object of the present invention is the provision of means which, in combination with the stock stop, will facilitate the removal of the finished work piece prior to the operation of the stop to position a new piece to be operated upon.

In the drawings accompanying and forming a part of this specification—

Fig. 1 is a front elevation of the lower part of a tapping machine illustrating the present invention.

Fig. 2 is a side elevation thereof.

Fig. 3 is a vertical section of the stop and its operating means but somewhat enlarged.

Fig. 4 is a horizontal section on the line 4—4 of Fig. 2.

Fig. 5 is a section on line 5—5 of Fig. 2.

Fig. 6 is a horizontal section as on line 6—6 of Fig. 7.

Fig. 7 is a detail of the construction of the stop, and

Fig. 8 is a layout of the fluid control system.

Similar characters of reference indicate corresponding parts in the several views.

Before explaining in detail the present improvement and its mode of operation, we desire to have it understood that the invention is not limited to the details of construction and arrangement of parts illustrated in the accompanying drawings since the invention is capable of other embodiments, and that the phraseology employed is for the purpose of description and not of limitation.

This invention is an improvement upon that shown and described in the A. E. Drissner et al. Patent 2,206,031, and only so much thereof as is deemed necessary herein for an understanding of the present invention has been illustrated and described and reference is made to that patent for a full disclosure of the operation of the complete machine.

Since, in this machine, the chuck is indexed, it is essential that the stop have considerable movement in order not to interfere with the indexing of the chuck and as certain sizes or lengths of work pieces require that the stop reach inside the chuck, it has been found that the swinging stop of the patent referred to is

sometimes impractical. Therefore, to overcome the disadvantages of that stop, the present improved stop has been designed which can have a very great travel and readily reach inside the chuck.

This improved stock stop 2 is located directly under and in line with the work holding chuck 3 and is designed to move in an up and down or vertical direction.

10 The stop is supported inside the base of the machine by suitable legs 4 set at an angle and so shaped that chips readily fall off, the legs 4 being suitably secured to the base of the machine.

15 In the present improvement, the stop is hydraulically controlled for raising and lowering it and comprises a supporting frame 5 housing the cylinder 5' having therein a piston 6 at the top of which the stop 7 is suitably and removably secured by means of the screws 8. Other stops may be substituted when desired for different sizes and shapes of work pieces to be operated upon.

20 Located below the stop 7 and also movable with the piston 6 is an extension 9 provided with suitable rods 10 projecting through openings 11 of lugs or extensions 12 of the cylinder supporting frame. These rods are threaded at their lower ends for the reception of nuts 13 which are adjustable to regulate or limit the up stroke of the piston 6.

25 Suitably secured to the front of the cylinder frame by a supporting arm or bracket 14 is a block 15 having a top surface 16 tapered toward the rear of the machine. This block is positioned slightly above the stop 7 when in its lowered position and the stop 7 has at its rear a beveled surface 17 and which is beveled in the same direction as the surface 16.

30 When the chuck 3 is opened to permit the release of the work piece, the piece drops down and strikes the beveled surface 16 or 17 or both, thereby being tipped so that it will fall toward the rear and drop into an inclined curved chute

35 18 suitably secured to the frame of the machine and be carried out the back of the machine. This chute, together with the beveled surfaces on the stop and block eliminate the necessity of the swinging damper employed in the hereinbefore mentioned patent.

40 In the operation of the present improvement, at the proper time when it is desired to open the chuck, the lever 19 (see Fig. 8) is released for operation and the operation of this lever 19 45 acts on a four-way valve 20 causing fluid to

pass through the line A to one end, as 21, of the chuck operating cylinder to effect the opening thereof to release the work piece which drops on the block or stop and is tipped into the chute 18.

After the chuck has been opened, pressure is built up in this line which extends to the pilot operated valve 22 through the line A'. On the end of this valve 22 is a pressure controlled pilot E which, when adjustable pressure is applied, allows fluid in the line B from a hydraulic pump to pass through the valve 22 into the line C connected with the bottom of the cylinder 5' which moves the piston 6 carrying the stock stop 7 upward into position properly to locate a new work piece within the chuck 3. Thus, it will be observed that, after the chuck is opened, there is sufficient delay to permit the finished work piece to be disposed of before the stop is again moved into operating position.

After the stop has been moved into position to receive a new piece of work, the lever 19 is released which causes the valve 20 to be opened in the opposite direction to permit fluid to pass through the line D to the closing side 21' of the chuck operating cylinder to close the chuck on the new piece.

The stock stop stays in its upward position until the chuck is closed whereupon pressure is built up in the line extending to the other end of the pilot valve 22 which also has on this end another pressure controlled pilot F which, when adjustable pressure is applied, causes the valve to operate in the opposite direction causing fluid from the line B to pass through the line G to the top of the cylinder 5' and effect a lowering of the piston 6 and thereby the stop 7.

After this has been accomplished, the interlocked machine operating lever is again released so that the operator can start the machine operating through its series of cycles to operate on a new piece.

While the beveled surfaces 16 and 17 and the shape of the curved chute are more practicable for certain sizes of couplings or castings yet the shape of these or any of them may be varied or eliminated for other sizes. In short, the work stop is moved vertically to a predetermined position to abut the lower end of the work before it is clamped in the chuck. It is, therefore, recessed before the work is threaded or otherwise operated upon. When the chuck is opened, the finished work drops down and when it contacts the sloping surfaces 16 and 17, it is deflected downwardly into the curved chute 18.

It is to be understood that, by describing in detail herein any particular form, structure or arrangement, it is not intended to limit the invention beyond the terms of the several claims or the requirements of the prior art.

Having thus explained the nature of our said invention and described a way of constructing and using the same, although without attempting to set forth all of the forms in which it may be made, or all of the modes of its use, we claim:

1. In a metal working machine having a horizontally positioned work holding chuck, a stock stop located below the chuck and vertically shiftable toward the chuck to position a work piece therein, and means for facilitating the removal of the work when the stop is in inoperative position, said means comprising a member having a tapered top surface cooperating with a tapered top surface on said stop.

2. In a metal working machine having a horizontally positioned work holding chuck, a stock stop located below the chuck and vertically shiftable toward the chuck to position a work piece therein, and means for facilitating the removal of the work when the stop is in inoperative position, said means comprising a member having a tapered top surface cooperating with a tapered top surface on said stop and an inclined chute cooperating with said tapered top surfaces.
3. In a metal working machine having a horizontally positioned work holding chuck, a stock stop located below the chuck and vertically shiftable toward the chuck to position a work piece therein, and means for facilitating the removal of the work when the stop is in inoperative position, said means comprising a member having a tapered top surface cooperating with a tapered top surface on said stop and fluid means for shifting said stop.
4. A metal working machine having a horizontally positioned work holding chuck, a stock stop located below the chuck and vertically shiftable toward the chuck to position a work piece therein, means for opening and closing the chuck, means for shifting the stop into and out of operative position, and means cooperating with the stop for facilitating removal of the work.
5. A metal working machine having a horizontally positioned work holding chuck, a stock stop located below the chuck and vertically shiftable toward the chuck to position a work piece therein, means for opening and closing the chuck, means for shifting the stop into and out of operative position, and means cooperating with the stop for facilitating removal of the work, said last means comprising a member having a tapered surface cooperating with a tapered surface provided on said stop.
6. A metal working machine having a horizontally positioned work holding chuck, a stock stop located below the chuck and vertically shiftable toward the chuck to position a work piece therein, means for opening and closing the chuck, means for shifting the stop into and out of operative position, means cooperating with the stop for facilitating removal of the work, said last means comprising a member having a tapered surface cooperating with a tapered surface provided on said stop and an inclined chute cooperating with said inclined surfaces.
7. In a metal working machine, the combination of a horizontally positioned work holding chuck, a stock stop located below the chuck vertically shiftable toward the chuck for positioning a work piece therein, means for opening and closing said chuck and shifting the stop into and out of operative position in timed sequence whereby the stop will have a delayed action, and means cooperating with the stop for facilitating removal of the finished work piece.
8. In a metal working machine, the combination of a horizontally positioned work holding chuck, a stock stop located below the chuck vertically shiftable toward the chuck for positioning a work piece therein, means for opening and closing said chuck and shifting the stop into and out of operative position in timed sequence whereby the stop will have a delayed action, and means cooperating with the stop for facilitating removal of the finished work piece and comprising a member having a tapered top surface co-

operating with a tapered top surface provided on said stop.

9. In a machine having a horizontally positioned work holding chuck, a stock stop located below the chuck and vertically shiftable toward the chuck for positioning a work piece therein, means for opening and closing the chuck, means for shifting the stock into and out of operative position, and means cooperating with the stop for facilitating removal of the work, said last means comprising a member located above and cooperating with the stop when in its inoperative position.

10. In a metal working machine having a horizontally positioned work holding chuck, a stock stop located below the chuck and shiftable vertically toward the chuck to abut a work piece to position it in the chuck, and fluid operated means comprising a piston carrying said stop adjacent to its upper end for shifting said stop vertically. 15 20

11. In a metal working machine having a horizontally positioned work holding chuck, a stock stop located below the chuck and shiftable vertically toward the chuck and adapted to abut a work piece to position it in the chuck, means for shifting said stop, and means cooperating with the stop for facilitating the removal of the work when the stop is in inoperative position.

12. In a metal working machine having a horizontally positioned work holding chuck, a stock stop located below the chuck in inoperative position a distance greater than the radius of the chuck and shiftable vertically transversely of the chuck through a distance approximately equal to the radius of the chuck to a point adjacent to the chuck to permit positioning a work piece therein, and means for shifting it.

ALFRED E. DRISSNER.
WILLIAM J. HOGG.
